UNITED STATES PATENT OFFICE

ENSLEY J. DONCASTER, OF RAYMOND, WASHINGTON

UNDERCUTTING DEVICE

Application filed May 28, 1928. Serial No. 280,998.

The invention is a device for holding saws while cutting on the under side of timber which may be driven into the log and readily adjusted.

5 The object of the invention is to provide a device for holding a saw while cutting on the under side of timber or the like.

Another object of the invention is to provide a device for holding saws for cutting 10 the under side of timber in which the position of the saw in relation to the timber may readily be adjusted.

A further object of the invention is to provide an under cutting device having adjusting means in which the adjusting means 15 is imbedded within the body of the device and not provided with springs or the like.

And a still further object of the invention is to provide a device for holding saws for 20 cutting timber which is durable and of a simple and economical construction.

With these ends in view the invention embodies a prong having a sharpened edge that is adaptable to be driven into a log, a hub 25 on the prong, an arm pivotally attached to the hub, means in the hub for holding the arm in various positions, and a grooved roller rotatably mounted on the outer end of the arm.

30 Other features and advantages of the invention will appear from the following description taken in connection with the drawings wherein:

Figure 1 is a view showing the device as 35 it would appear in use.

Figure 2 is a side elevation of the device.

Figure 3 is an edge view of the device.

Figure 4 is a cross section on line 4—4 of Figure 3.

40 In the drawings the device is shown as it would be made wherein numeral 1 indicates the prong, numeral 2 the arm and numeral 3 the grooved roller.

The prong 1 may be of any suitable 45 sign and the arm 2 attached to it in any suitable manner. In the design shown the outer end of the prong is provided with a sharpened edge 4 and a hub 5 is rigidly mounted upon the prong as shown in Figures 2 and

50 3. The hub 5 is provided with an opening

6 in which a pin 7 is slidably mounted and the pin 7 is provided with a notch 8 in which a projection 9 on the hub may extend which will permit the pin 7 to slide and at the same time hold it in the hub.

55 The arm 2 may be made as shown and provided with a plurality of holes 10 to correspond with the opening 6 so that the pin 7 may extend into one of the holes 10 to hold the arm 2 in relation to the prong. The arm 60 2 is pivotally mounted upon the pin 11 in the center of the prong and on the outer side of the arm is a washer 12 in which the outer end of the pin 11 is riveted as shown in Figure 4. It is understood however that the arm 2 may 65 be attached to the prong in any other suitable manner. In the outer end of the arm 2 is a pin 13 upon which the grooved roller 3 is rotatably mounted and in the outer end of the pin 13 is a pin 14 to hold the roller 70 upon the pin. The roller 3 may be of any other suitable design and may be mounted in any other suitable manner.

75 It will be understood that changes may be made in the construction without departing from the spirit of the invention. One of which changes may be in the design of the prong, another may be in the use of other means for attaching the arm to the prong, and still another may be in the use of other means 80 for adjustably supporting the arm upon the log.

85 The construction will be readily understood from the foregoing description. To use the device the prong may be driven into a log as shown in Figure 1 and by withdrawing the locking pin the arm 2 may be set at such an angle that the roller 3 will hold the saw against the under side of the log and it will be observed that as the saw cuts into the log 90 the position of the roller may readily be adjusted by withdrawing the pin and moving the arm about the point at which it is attached to the prong. It will therefore be observed that this device provides a very efficient means for holding a saw while undercutting a log, makes it possible to adjust the position of the saw as it cuts into the log and at the same time is of a very simple and durable construction.

Having thus fully described the invention, what I claim as new and desire to secure by Letters Patent, is:

In a device of the class described, a bar having a sharpened end, a hub on the said bar, an arm pivotally attached to the hub, a plurality of openings in the arm arranged in a circle about the said pivot point, a pin slidable in the said hub, said pin having a recess and said hub having a projection extending into the said recess, said pin being adaptable to engage the openings in the said arm to hold the arm in relation to the bar, and rotatable means at the outer end of the arm for supporting a saw.
